Robert M. Richardson & Mills Richards
Inventors

Office Specified - Reference is made to the Letters Patent now making, part of the same containing a description in the words of the said Inventors Robert M. Richardson and Mills Richards themselves of a machine for picking leather that is to be detailed.

The frame or bench is two feet wide a half high, two feet and a half wide, and three feet and four inches long. This frame would be more convenient for a shoemaker without legs or posts, for then he can place it on his cutting table, therefore it will be more convenient and less cumbersome. The carriage consisting of a piece of wood, eighteen inches long and two wide, the running part of said carriage is iron flat fastened to the center side of the carriage, which iron runs through ten steel or iron rods five on each side these rods are fastened in two blocks of timber lying each side of said carriage the timber frames to the bench. On the above mentioned carriage on the right side is fastened two or three rings or gages made of steel with the notches upward. These clamps which are fastened on the upper side of said carriage are seven inches high and eighteen inches long made of wrought iron and are in two parts, one part of said clamp is made fast on the left side of said carriage by a curved piece of timber the same length of the clamp so the other part on side of clamp which is fast to open, but at the bottom three iron yokes carrying bars which bars are fastened in the carriage the lower part at bottom of the clamp are four inches apart, the side bars which are up and down are bent in order to bring the top bar or jaws together for the purpose of holding the leather. The clamps are bent with three steel springs set in the carriage and rest against the side bar of the clamp that opens. Clamp opens by pulling the right foot on a treadle fastened at the right side of the bench, from the treadle is a strap which goes over the roller on the right side of the bench and reaches to the clamp with an iron hook on the end which hook hooks to the middle bar of said clamp. These clamps are hung in such a manner that they can be taken out after the leather is picked and set on other bench and so on. Therefore no demand of machinery of the business of the stock required it to have a number of pairs of clamps fitted to run in

one attachment of the same size and description as above specified. The aul bar
bar is nine inches long, and five eighths of an inch square made of steel, in the
middle of the clamps is a screw bar for the purpose of screwing on and off, as the
end of this bar is a crook with a hole through it from part, another slips through
two bars which bars are fastened in a block of wood, the aul bar is guided by these
spurrs on the under side of the bar between the bars fastened to the block, the other
two spurs are set in the block and stand upright and rest against the side of the
bar, the block is fastened. The right side is the clamp in two holes which posts
are found on the centre of the handle, the posts sufficient in height to raise the aul
bar to the height of the clamps. The nozzle post or roller is made about long and
staves perpendicular turning in two steel beds, one at the bottom and the other
at the top, which bars are fastened in a post which post is framed in the further
end of the handle, the middle bar is ten feet long including the elbow, and is
fastened to the upper end of the roller and reaches to the aul bar and there has
a mortice for a sheath or piece of iron, which sheath is fastened in the mortice
with a pin the other end of the sheath is fastened in the crook of the aul bar with
a steel pin, in the end of the nozzle bar is a handle of wood for the purpose of put-
ting the machine in motion by the hand. I conceive that the aul may be car-
ried by the foot by having a treadle and steps to carry it forward on a straight
or spring to carry it back. At the bottom of the roller is fastened an arm
which arm reaches to the left five inches made square of iron, on each arm slips
a bar or double swivel of iron, which bar slips on and off to give the different
lengths of stitches, which bar is fastened with a wedge or screw. The hand is
eighteen inches long one end is fastened to the bar or double swivel with a steel
pin, the other end reaches under the aul and rests on the nay arms or gauges
for the purpose of moving said carriage and clamps. The aul are fixed
in a number of aul shafts which aul shafts are to be screwed in or out of the aul
bars as the business requires. The above mentioned machine can be varied larger
or smaller with the same proportion above specified. I conceive that this ma-
chine can be varied in several ways, the carriage can be moved with a screw
and drag and likewise the clamp made fast and the aul fixed on the carriage
and moving in the like manner as the clamp.
